UNITED STATES PATENT OFFICE

153,324

DESIGN FOR A ROTARY WINGED AIRCRAFT

Paul H. Stanley, Huntingdon Valley, Pa., assignor
to Autogiro Company of America, Philadelphia,
Pa., a corporation of Delaware

Application November 9, 1946, Serial No. 134,682

Term of patent 14 years

(Cl. D71—1)

To all whom it may concern:

Be it known that I, Paul H. Stanley, a citizen of the United States, residing at Huntingdon Valley, in the county of Montgomery and State of Pennsylvania, have invented a new, original, and ornamental Design for Rotary Winged Aircraft, of which the following is a specification, reference being had to the accompanying drawings, forming a part thereof.

Figure 1 is a side elevational view of the rotary winged aircraft of the invention.

Figure 2 is a front elevational view of the craft shown in Figure 1.

Figure 3 is a top plan view of the craft shown in Figure 1.

Figure 4 is a perspective view of the aircraft shown in Figure 1.

I claim:

The ornamental design for a rotary winged aircraft, as shown.

PAUL H. STANLEY.
